UNITED STATES PATENT OFFICE.

LOUIS REICHERT, OF SCRANTON, PENNSYLVANIA.

AUTOMATIC DRILLING-MACHINE.

No. 926,606.

Specification of Letters Patent.

Patented June 29, 1909.

Application filed March 16, 1908. Serial No. 421,752.

To all whom it may concern:

Be it known that I, LOUIS REICHERT, a citizen of the United States, residing at Scranton, in the county of Lackawanna and State of Pennsylvania, have invented certain new and useful Improvements in Automatic Drilling-Machines; and I do hereby declare the following to be a full, clear, and exact description of the invention, such as will enable others skilled in the art to which it appertains to make and use the same.

This invention relates to improvements in drilling machines, and particularly to machines for drilling fine work as small pinions, staffs, etc. used in watches, clocks, and the like, and has for an object the provision of a drill that will quickly and accurately drill a hole any place desired.

Another object in view is the provision of a drilling machine arranged to receive the end of a staff or shaft used in mounting wheels in a clock or watch, and boring a hole longitudinally in said shaft preparatory to securing a bearing member therein.

A still further object in view is the provision of a drilling machine that is adapted to receive an article to be drilled and then be set for drilling a hole a proper distance and then put into operation and left to automatically finish the drilling operation.

A further object in view is the provision of a spring driven machine for rotating a drill at a comparatively high speed for drilling a hole in any article desired, the machine being formed with a guiding or dividing plate for holding the article in position that is designed to be drilled, and mechanism for yieldingly forcing the drill against the article being drilled.

With these and other objects in view the invention comprises certain novel constructions, combinations, and arrangement of parts as will be hereinafter more fully described and claimed.

In the accompanying drawing: Figure 1 is a side elevation of a drilling machine formed according to the present invention. Fig. 2 is an end view of Fig. 1. Fig. 3 is a section through Fig. 1 approximately on line 3—3, certain parts being broken away. Fig. 4 is a fragmentary top plan view of Fig. 1. Fig. 5 is an enlarged detail view of a guide or dividing plate and means for holding the same in position.

In constructing a drilling machine according to the present invention the same is made

with a frame having an upper plate or member 1, and also a plate or member 2, together with a plurality of uprights 3 arranged to hold the plates spaced apart and yet firmly in position. Mounted between plates 1 and 2 is a spring motor 4 arranged to convey power through gears 5 and 6 and pinions 7 and 8 to a drill carrying shaft or spindle 9. The gear 6 in addition to meshing with pinion 8 also meshes with a pinion 10 which has connected therewith a gear 11 that meshes with a pinion 12. Pinion 12 is rigidly mounted upon a shaft 13 which in turn has rigidly secured thereto a fan or brake 14 used to limit or prevent a too high speed upon shaft or spindle 9. By this construction it will be seen that power is connected with shaft or spindle 9 and with brake 14 so that when one moves, the other will also move, and when brake 14 in revolving is retarded by the air, spindle 9 will also be retarded and limited in its speed. This will prevent the spindle from rotating a drill 15 carried thereby from going too fast and thereby becoming heated.

The spindle or shaft 9 has pinion 8 rigidly secured thereto so that when pinion 8 is rotated as heretofore described the spindle will also be rotated. In order to form a proper bearing and also a comparatively long bearing for spindle 9, tubular extensions 16 and 17 are provided that accommodate the end of the spindle. Spindle 9 at one end projects above plate 1 and is formed or provided with a bearing point 18 that is preferably formed of hard material. The opposite end to point 18 is designed to be positioned in bearing 17 and to be formed hollow from the end up to a cut-away portion 19 for accommodating drill 15.

Positioned on plate 2 is a guide or dividing plate 20 arranged to receive a shaft or staff 21 of a wheel 22 and designed to hold the same in position for drill 15 to drill a hole longitudinally of the shaft. The guide 20 is arranged with a plurality of apertures 23 of various sizes for accommodating various sized shafts 21. Formed on the periphery of the guiding plate 20 is a plurality of teeth or projections 24 designed to accommodate a catch 25 that is designed to engage the projections 24 and by its spring action be held in contact therewith. It will, however, be obvious that the catch 25 may be pivotally mounted and a spring used for holding the same in contact with projections 24. An adjusting member 26 is provided that has a

flat side that engages member 25 when it is desired to have the same engage projections 24 and when it is desired to disengage catch 25 member 26 is partially rotated and by 5 such rotation will move catch 25 to the dotted position shown in Fig. 5.

A receiving member or chuck 27 is provided for receiving one end of shaft 21 while the shaft is being drilled, and in order to prevent the shaft from rotating a dog 28 is used, as clearly seen in Fig. 3. Receiving member or chuck 27 is arranged to be slidably mounted into a sleeve 29 that in turn is rigidly secured to a support 30. The receiving member 27 may move toward or from plate 2 and guiding plate 20 for receiving various sized articles and when the article has been properly placed in position a set screw 31 is tightened for holding chuck or 20 receiving member 27 in its adjusted position.

Bearing against the point 18 is a yielding tension member 32 that is slidably mounted in a sleeve 33 and is designed to be pressed by spring 34. Spring 34 is designed to be 25 compressed or brought under tension by a sliding bar or shaft 35 as clearly seen in Fig. 2 and when brought under tension bar 35 is locked by having a lug 36 projecting therefrom engage a rack 37 formed upon sleeve 33. 30 Sleeve 33 is rigidly secured to a support 37' that is pivotally held in position by a securing member 38 and a tensioning or locking member 39. The support 37' is formed with a slot 40 that is struck upon the arc of a 35 circle with member 38 as a center so that when it is desired to remove shaft or spindle 9 together with drill 15 all that will be necessary will be to loosen the tension member 39 and swing support 37' upon its pivot 38 until 40 sleeve 33 has moved from above the spindle 9. The spindle then may be moved longitudinally and again replaced as may be desired. Support 37' is also formed with an extension 41 that is designed to engage a 45 swinging bar or extension 42 of the spring motor 4 for limiting the swinging movement thereof. By the construction of sleeve 33 spring 34 and surrounding parts a yielding tension may be brought upon spindle 9 for 50 yieldingly pressing drill 15 in its work.

In operation when it is desired to drill an article as, for instance, a shaft as 21 the same is placed in position as seen in Figs. 1 and 2 and drill 15 and spindle 9 placed in 55 position if not already in position. Sliding shaft or member 35 is then pressed downward until spring 34 has been brought under tension to any desired degree for drilling any desired distance into shaft 21. A locking 60 member 43 is then brought over so as to prevent the rotation of brake 14 by means of the operation of a lever 44. When brake 14 is thus locked against movement the spring motor 4 is wound up to any desired tension 65 and after such winding lever 44 is moved for

causing locking member 43 to be disengaged from brake 14. This will permit brake 14 to move and consequently spindle 9 and the other moving parts connected therewith. As will be evident this will rotate drill 15 and as 70 the same is pressed by spring 34 a hole will be bored through shaft 21. As this takes some little time the machine usually is set aside out of the way and will continue to drill automatically the hole in the shaft and 75 when the hole has attained a predetermined depth as regulated by the tension of spring 34 the drill 15 will cease to remove any matter from the shaft 21. If the motor 4 has not run down by this time the same will continue to run until the spring is unwound, but will not continue to drill or remove matter from the shaft 21. From this it will be evident that the machine when once set will 80 drill a hole a predetermined distance and 85 then stop drilling, the operation being automatic after the drill has once been set into motion. In order to accommodate the matter drilled or removed a counter-sunk or hollowed-out portion 45 is provided in member 90 2. This counter-sunk portion may be cleaned out from time to time as may be desired, either by removing through an opening left by guide or dividing plate 20, or dividing plate 20 may be entirely removed and 95 the countersunk portion cleaned. The dividing plate or guide 20 does not entirely cover counter-sunk portion 45 and ordinarily the opening left will be sufficiently large for removing the borings of the drill. 100

What I claim is:

1. In a drilling machine, a spindle, a work-rest provided with a plurality of openings for receiving and guiding an article, said rest also being provided with a plurality of teeth, 105 a spring pawl engageable with the teeth interchangeably, and a rotatable member constructed and arranged to permit of such engagement of the pawl with the teeth when in one position, and to hold the pawl out of such 110 engagement when turned to another position.

2. In a drilling machine, a spindle, a work-rest in the nature of a wheel provided with a plurality of openings for receiving an article, the said wheel being formed upon its periphery with a plurality of teeth, a spring pawl engageable with the teeth interchangeably, and a rotatable member constructed and arranged when in one position to permit of engagement of the pawl with the teeth, and when rotated to another position to prevent such engagement. 115

3. A drilling machine comprising a frame, a spindle, a guide for the spindle, a seat for 125 one end of the spindle, a spring bearing against the seat, and means for adjusting the tension of the spring.

4. A drilling machine comprising a frame, a spindle, a guide for the spindle, a sleeve, a 130

seat for one end of the spindle, said seat being received in the sleeve and movable longitudinally thereof, a spring arranged within the sleeve and bearing against the seat, and 5 means adjustably held within the sleeve for varying the tension of the spring.

5. A drilling machine comprising a frame, a spindle, a guide for the spindle, a sleeve, a seat for one end of the spindle, the said seat 10 being movable in the sleeve, a spring arranged within the sleeve and bearing against the seat, and means whereby the tension of the spring may be varied.

6. A drilling machine comprising a frame, 15 a spindle, a guide for the spindle, a sleeve, a

seat for one end of the spindle arranged for movement in the sleeve, a spring arranged within the sleeve and bearing against the seat, a rod slidably received in the sleeve, the said sleeve being formed with a slot and 20 along one edge of the slot with rack teeth, and a projection on the rod engageable with the said rack teeth.

In testimony whereof I affix my signature in presence of two witnesses.

LOUIS REICHERT.
